INNERSOLE FOR SHOES

Millins W. Prouty, Braintree, Mass., assignor, by
mesne assignments, to Certified Leathers, Inc.,
a corporation of Massachusetts

Application December 20, 1932
Serial No. 648,063

3 Claims. (Cl. 41—17)

This invention relates to improvements in shoes.

More especially it relates to improvements in dealing with the innersole, sometimes called the insole; and it deals with the constructing of a finish, on this element which the makers of fine shoes have hitherto thought it necessary to cover and to conceal from view, because of the shoe industry not having hitherto discovered any practicable way to impart to it a satisfactory finish, at a practicable cost.

The results are particularly useful with respect to women's shoes, in which the having of a completely finished appearance in all parts of the shoe is a necessary element for rendering the product marketable as a fine shoe.

The invention provides a finish, such that the innersole may be left exposed to view in a fine shoe; may be open to access by any person to examine it in the shoe; and may even bear a certification as to kind or quality; and the invention provides other advantages which result in the making of a better shoe at lower cost.

In the construction of a shoe the innersole is the primary and central element to which the other parts of the shoe are secured; in the completed shoe it is a sort of backbone or spinal column, by which the shoe is held together; and it also, because of proximity to the wearer's foot, has important influence upon comfort. A careful purchaser therefore needs reliable knowledge as to the material and characteristics of the insole.

For many years it has been recognized that a proper material is found in leather. Leather stock for innersoles has been developed to a high degree of strength and flexibility; yet meantime the finish of insole stock has not attained an improvement in character which fits it for exposure to view in a fine shoe.

For the commercial marketing of a fine shoe the element of "finish" is a very important feature of the shoe. In consequence, manufacturers build into their fine shoes surfaces, for all visible parts of the shoe, in which aesthetic appeal has been developed to a high degree. For the bottom of the inside, good practice has hitherto included a "sock lining", usually of kid, sheep skin, or other very thin leather, having a kind of surface which can be given a finish, the purpose of which sock lining is to cover and conceal the crude appearing innersole. The introduction of a sock lining causes expense for the material, and also for the labor involved in its insertion; and it adds nothing to the real value of the shoe.

as regards utility. In fact it detracts, since in a percentage of cases it works loose, becomes wrinkled, has to be pulled out, and leaves a rough pasty surface, with consequent discomfort. But it is considered necessary,—in order to make the shoe saleable, and to make the interior bottom finish of the shoe be in keeping with all other exposed parts of the shoe.

Furthermore, a repercussion follows, to the injury of the shoe industry. The fact that sock linings are put into fine shoes is taken advantage of by some manufacturers to substitute inferior materials for genuine leather innersoles, under a sock lining. The substitutes are of various sorts, some being in the nature of paper; others of cotton fibre; or even being sheets of wood pulp having pores filled with rubber, as to which wearers find practical objection in addition to the inferiority of strength and durability of the substituted material.

The present invention renders a sock lining unnecessary, by making it commercially practicable for the manufacturer to make his fine shoes saleable, with the innersole left exposed to view. This is accomplished by constructing a finish on the insole, before it is built into the shoe, by a treatment whose primary purpose is realized only when that sole is playing its part in the interior aspect of the completed shoe. The insole, then exposed, displays an appearance in which the observer does not notice the characteristic crudity of appearance of good insole stock. Thereby, because of the accessibility of its insole for examination, a fine shoe becomes able to speak for itself as to its quality.

If desired, the sole can be made literally to speak for itself, certifying in words as to the character of its material. But whether this certification be made or not, the invention renders it unnecessary to introduce a sock lining. Thereby it effects in manufacturing costs substantial saving, which may range from two to ten cents per pair, and yet it renders the shoe marketable as a fine shoe,—and at a corresponding price, according to its true merit.

The omission of the sock lining affords a safeguard to the shoe purchaser, who otherwise may be misinformed by an over confident sales person, or an unscrupulous one, because of the inability to see exactly what the sole is, when covered by a cemented sock lining. Also, when a shoe is made to sell at a given price, the manufacturer, by omitting thus the sock lining, is able to put in a better quality of insole.

The difficulty which has hitherto rendered it

necessary to conceal leather insoles does not arise from any lack of effort to finish them. Many attempts to do that have been made; but the trouble lies with the peculiarity of leather itself, whose grain, or split surface under the grain, has a characteristic lack of uniformity which prevents it from acquiring the look of a perfect finish, such as kid and sheep skin may acquire. But the invention makes it possible to finish that very same leather surface so that it can be used with satisfaction. As an illustrative example, one may refer to flexible split leather. This is an economical material for innersoles, because it is made by removing a thin sheet of the grain portion of a side of leather, and the selling of this grain for other uses reduces the cost of the remainder, which remainder is suitable for insoles because it has the necessary fibre strength for withstanding stitching strain; is substantially stable as regards ability to stretch; and has a desirable flexibility which makes for comfort of the wearer, as does also its ability to absorb perspiration from the stocking.

In attaining its end, the invention may employ the usual flexible split leather, finished as well as the tanners are accustomed to finish it, this finish, however, though it be the best that can be done, being nevertheless something which the shoe industry has hitherto regarded as not being adequate for the needs of a fine shoe. Seen under a microscope of adequate power this surface, if buffed, will present bushy masses of fibre, left with raw ends by the splitting of the leather; while if the surface has been finished by filling and polishing or jacking, the surface will have become scaly with edge cracks running in all directions and occasional pits and differences of shading; and in the case of grain leather the surface is somewhat similarly scaly.

These peculiarities are not seen as such by the ordinary eye, but they are mentioned as being among the causes which possibly contribute to the undoubted characteristic of crudeness of aspect which the best of insoles, of commercial grade has, when built into a shoe and lying beside the exquisite finishes which exist in all other parts of the shoe. Another element, contributing to the somewhat mottled aspect, may be the difference of direction in which adjacent whorls of fibres lie at the surface of the leather.

The invention deals with this surface by superimposing thereon scattered lines or marks which are prominent enough to engage the attention of a beholder's eye and to throw into inconspicuous background those irregularities which formerly characterized the whole surface of the leather. It will be understood that the differences between various portions of the insole leather, as heretofore made, and as described above, are really slight, when considered in an absolute sense, although they are enough to produce the visual effect of relative crudity as above expressed, and it is that crudity which engages the eye and commands the attention of the observer. But when one's eye is engaged by the said scattered lines, or marks, and the attention is preempted by them, the slight differences between adjacent portions of the leather surface do not catch the attention,—in fact it becomes hard to fix the attention upon them so as to perceive them,—and a general impression of uniformity of the background is the predominant characteristic which comes to the eye, from that part of the picture on which the attention is not now focused.

It is desirable that the superimposed marks be

impressed in some sort of a pattern, covering the whole of the surface in the sense that an open-work pattern covers the whole of a certain area while in fact leaving uncovered large portions of the area. The marks may preferably be no different in color from the surface itself, being merely such a slight darkening of it as can be made by impression of a heated roller sufficient to make depressed lines and marks without scorching them black. This gives a two-toned effect on the face of the insole, in which the true leather color is preserved. The benefits of the invention may be had however, provided one's artistic sense is at the same time satisfied, where the lines are more pronouncedly in contrast with the leather surface. Moreover, there is some advantage in changing the leather surface from its natural leather color, as for example changing it to a blue, a step to be executed in the tanning process by any suitable method.

In the accompanying drawing the representation of a surface of the innersole is lined with the conventional representation of blue for two reasons, one being in order that the coloring of it differing from the natural leather color may be shown as this is an advantageous feature which may be employed if desired; and the other being to modify the sharpness of contrast (black and white) which, under the rules for making patent drawings, would strike the eye of the person looking at the drawing, because such a sharpness of contrast will not ordinarily be a desirable feature, and the close ruling of the background lines representing the leather surface makes this contrast less pronounced between the various parts of the completed insole. No attempt is made in the drawing to portray the finish of the other parts of the shoe which, however, will not have such sharp contrasts as the drawing indicates, but will be as shoes are ordinarily made.

The superimposing of these marks on the background, which consists of the finished surface of innersole leather as heretofore finished, may be done when the side of leather is still whole; or it may be applied to the whole of the innersole which has been cut therefrom. Each is a convenient and economical way of making the impression by an engraved roller or by such other means as are to be employed.

It is sufficient that the lines thus impressed be very narrow, for example, having a width of the order of one one-hundredth of an inch; and that the impression be very shallow, barely enough for its edges to cast a shadow, for which not much more than a microscopic depth of impression is needed, a narrow trench clearly felt, or enough to be sensed by one's finger nail, but not appreciably felt by the sole of one's foot.

The essential characteristic of the impression to be made on the face of the innersole is not that it should be a pattern of aesthetic value, although of course it would be natural that one should select an attractive design. But the success of the invention depends rather on the breaking up of the microscopically ragged fibrous surface of the leather, or the scaly grain surface, or filled surface, of the leather, with areas varying slightly from each other in shade of color, by the introduction of smooth areas or lines of microscopic depth which naturally draw one's eye and attention away from the adjacent unaltered parts of the surface; and which, having in themselves a quality of uniformity, impart the impression of uniformity to the entirety of the surface over which they are spread. Their

own uniformity may be one of deepness or smoothness of impression, or of color, or of unity of design even though not uniform in the above respects.

appears to the eye from this patent drawing in black and white, but effects a focus of the eyes involuntarily upon the area of each little mark. Inasmuch as the pre-treated innersole, of this combination of insole, outsole, upper, and lining, does not need to be covered, the customary sock lining may be omitted, with incidental saving of a substantial amount in each pair of shoes; and as this special treatment of the innersoles has increased their cost but slightly, the net saving effected by the elimination of the sock lining is a substantial sum, and at the same time the shoe as a whole is better. And the shoe thus made includes the important element that the retailer in buying his stock, and the retail purchaser examining a shoe that looks like a fine shoe, can see and be satisfied as to the material of the innersole. Beyond this, if words be incorporated in the pattern impressed, the fully exposed innersole, for the benefit of purchasers who are not expert in fibrous materials, may inoffensively bear its own guarantee as to its material.

Of course the pattern is not necessarily applied in the preferred manner herein described, but 100 may be put on in other ways, to obtain an effect of the same kind.

In the drawing the marks superimposed on the insole are represented as lines at 22 having parallel continuity; as block areas 24, as in parts of the conventionalized blueberry and leaf, and in short vari-directional lines as in the letters 26 of the words which are visible stating the nature of the material of the innersole. These lines, if impressed with pressure of a heated engraved die roller may preferably be so shallow that they would not show in the sectional drawing of the innersole 12 in Figure 1; and the same would be true if the lines were made by deposit of a foreign material, as ink, on the surface of the innersole 12. In each case, the effect of the mark, either by shadow or by difference of aspect of applied material, even though the difference or shadow be but slight, is to give a fibre-free aspect to the small bit of the sole which is covered by the mark, and to continue that aspect with an effect of uniformity over the whole region over which the marks are spread, with the involuntary action of one's eye resting upon this rather than the unaffected surface of the leather. 125

I claim:

1. A shoe, having an outer sole, an upper and a finish lining, combined with an innersole, in which shoe the upper surface of said innersole is exposed to view as an interior face of the shoe, the material of the said innersole being of a variety whose natural aspect lacks refinement; said exposed innersole surface being substantially free from lesion and being superficially dressed with marks impressed visibly on its surface, whereby the exposed innersole, as a whole, has a finished aspect notwithstanding the said natural aspect of its material.

2. A shoe, having an outersole, an upper and 140
a finish lining, combined with an innersole, in
which shoe the upper surface of the said inner-
sole is exposed to view as an interior face of
the shoe, the material of the said innersole being
of a variety whose natural aspect lacks refine- 145
ment; the said exposed innersole surface being
substantially free from lesion and having marks
visibly impressed thereon, said marks being
spread over the surface thereof as a pattern
thereon and being a legible indication with re- 150

gard to the material of the innersole, whereby the exposed innersole surface as a whole has a finished aspect, notwithstanding the said natural aspect of the material of the innersole.

5 3. As a new article of manufacture, innersole material for a shoe, made of split leather, having its split surface substantially free from lesion

and having that aspect of lack of refinement, which naturally characterizes such a surface, relieved by the presence of an openwork pattern impressed on a major part of said surface, whereby the said surface is refined for standing exposed to view in a completed shoe. 80
